UNITED STATES PATENT OFFICE.

HUMPHREY EVANS, OF MILWAUKEE, WISCONSIN, ASSIGNOR TO HOLEPROOF HOSIERY CO., OF MILWAUKEE, WISCONSIN, A CORPORATION OF WISCONSIN.

FABRIC STRAIGHTENING AND GUIDING DEVICE.

1,375,041.

Specification of Letters Patent. Patented Apr. 19, 1921.

Application filed June 19, 1920. Serial No. 390,250.

To all whom it may concern:

Be it known that I, HUMPHREY EVANS, a citizen of the United States, residing at Milwaukee, in the county of Milwaukee and 5 State of Wisconsin, have invented certain new and useful Improvements in Fabric Straightening and Guiding Devices, of which the following is a specification, reference being had to the accompanying drawings, forming a part thereof.

10 The main object of this invention is to untwist or uncurl and straighten and to guide ribbed or ridged fabrics parallel with the ribs, ridges or wales thereof, for performing certain operations thereon such as 15 folding, imitation seaming, stitching, etc.

It consists in the construction, arrangement and combination of parts as herein-after particularly described and pointed 20 out in the claims.

In the accompanying drawing like characters designate the same parts in the several figures.

Figure 1 is a front elevation of a fabric straightening and guiding device embodying the invention, and of an overstitch sewing or selvage seaming machine, in connection with which the device is designed to be used; Fig. 2 is an enlarged plan view of a 25 portion of the straightening and guiding device and of the sewing machine; Fig. 3 is a vertical cross section on the line 3—3, Fig. 1; and Fig. 4 is an enlarged view of a portion of the brush and supporting arm of the 30 straightening and guiding device in connection with a piece of knitted fabric showing the ribs, ridges or wales exaggerated.

The device may be adapted to untwist or uncurl, and straighten and to guide knitted 40 or other ribbed or ridged fabrics parallel with the ribs, ridges or wales thereof, for performing various operations thereon, such as folding, stitching, etc.

For the purpose of illustration the device 45 is shown and will be described as specially designed for folding and stitching or seam- 50 ing seamless tubular hosiery, underwear and the like, with a sewing machine provided with folding and feeding mechanism for withdrawing the fabric from the straightening and guiding device and presenting it in proper position and condition to the needle or stitching mechanism of the sewing machine.

The device comprises a fabric supporting 55 arm 1, mounted adjacent one end in a substantially horizontal position on a post or standard 2, which may be screwed or otherwise fastened by a foot flange or plate 3 to a table or shelf 4 on which the sewing machine 5 is placed. This arm as shown, is of cylindrical or tubular form, and may be conveniently made of metal with a convex rounded upper fabric-supporting surface.

Adjacent its free or unsupported end, the 60 arm is formed with a transverse recess, in which a brush 7 is fastened. The brush is preferably of circular form as shown, and of smaller diameter than the arm 1, and is provided with radiating bristles of hair, 65 fiber, wire or other suitable flexible material, which project on the upper side a short distance above the adjacent curved or rounded fabric-supporting surface of the arm, as shown in Figs. 1 and 4. The brush is centrally fastened in the arm by a screw 8, on which it is angularly adjustable so as to bring unused bristles into operative position when the exposed bristles on the upper 70 side are worn down. The central opening 75 in the brush is made larger than the screw, so that the brush can be adjusted vertically to vary the extent of projection of the brush bristles above the fabric-supporting surface of the arm.

In a longitudinal slot of the arm 1, a pressure arm or lever 10 is pivoted on a cross pin 11, one end extending below the arm and being bent upwardly or formed with an upwardly projecting finger 12, adjacent 80 the brush end of the arm. The other end of the arm or lever 10 projecting above the supporting arm 1, is connected by a spring 14 with a bracket 15, fastened to the arm 1 or the post or standard 2.

Adjacent the brush 7 the arm 1 is formed in its upper side, as shown in Figs. 1 and 2, with opposite finger notches 17, separated from each other by a narrow central partition piece.

The end of the pressure arm or lever 10 opposite the finger 12 is connected by a cord or chain 18 passing downwardly through the post 2 and table 4 underneath and over guide sheaves or pulleys 19 and 20, to a 105 treadle or foot lever 21, by which the finger end of said pressure arm or lever is elevated against the tension of the spring 14 toward

the arm 1, as indicated by dotted lines in Fig. 1, for placing a seamless tubular article such as a stocking, on the arm 1.

The upper side of the arm 1 is arranged 5 centrally in alignment with the meeting faces of the feed wheels 23 of the sewing machine 5, just below the path of the needle 24.

To determine the proper position of the 10 fold for starting a longitudinal mock or imitation seam centrally in the back of a stocking, the arm 1 is provided at the end adjacent the sewing machine with gage points 26.

15 In the operation of the device for forming mock or imitation seams centrally along the backs of seamless stocking legs, the finger end of the arm 10 being elevated as indicated by dotted lines in Fig. 1, a stocking is 20 placed on the arm 1 with the corners of the heel on the gage points 26, in position for starting a seam. The operator then grasps the fabric with a thumb and finger of each hand, forming a fold over the upper end of 25 the finger 12 and the partition piece between the notches 17, and enters the fold thus formed between the feed wheels 23. The arm or lever 10 being released, is 30 pressed downwardly by the spring 14 against the under side of the stocking, as shown in Fig. 3, thereby holding the fabric in engagement with the bristles on the upper side of the brush 7, which by engagement with the ribs or wales of the fabric, 35 untwists or uncurls and straightens it, so that a straight fold and seam will be formed parallel with the ribs or wales of the fabric without further care or attention on the part of the operator.

40 After the fold is entered between the feed wheels above which it projects into the path of the needle 24, the stocking is drawn by the feed wheels over the brush 7, and is straightened by engagement of the brush 45 bristles with the ribs or wales of the fabric, as shown in Fig. 4, so that the fold, which is continued by the action of the feed wheels and the seam will follow a straight line parallel with the ribs or wales of the fabric.

50 Various changes in the details of construction and arrangement of parts of the device may be made to adapt it to operate on knitted or ribbed fabrics of different kinds and articles of different shapes so as to 55 straighten and guide them in a direction parallel with the ribs or wales of the fabric for performing various operations thereon such as folding, seaming or stitching, without departure from the principle and scope 60 of the invention as defined in the following claims.

I claim:

1. In a fabric straightening and guiding device the combination of a support and a 65 brush mounted thereon and adapted by en-

gagement with ribs of a fabric moved over it to straighten and guide the fabric parallel with the ribs thereof.

2. In a fabric straightening and guiding device the combination of a fabric supporting arm formed with a transverse recess and a bristle brush mounted in said recess with bristles projecting from the fabric supporting surface of the arm and adapted by engagement with ribs of a fabric moved over 70 said surface to straighten and guide the fabric parallel with its ribs.

3. In a fabric straightening and guiding device the combination of a fabric supporting arm, a brush mounted thereon and means for yieldingly pressing a fabric moved along 75 the arm against the brush.

4. In a fabric straightening and guiding device the combination of a rounded arm supported adjacent one end thereof and formed adjacent its free end with a transverse recess, and a circular brush mounted and angularly adjustable in said recess with bristles projecting therefrom beyond 85 the adjacent fabric supporting surface of 90 the arm.

5. In a fabric straightening and guiding device the combination of an arm supported adjacent one end and provided adjacent the other end with a bristle brush projecting 95 above the upper fabric supporting surface of the arm, a lever pivoted to said arm, a spring tending to force the lever downward below the brush and to hold a tubular article supported on the arm in yielding engagement with the brush, and means for turning 100 the lever upward toward the brush end of the arm.

6. In a fabric straightening and guiding device the combination of a fabric supporting arm provided adjacent one end with a brush projecting upwardly therefrom, a pressure arm pivoted to the first arm and tending normally to press a tubular article 105 downward against the brush, and means for shifting the pressure arm upward toward the brush for placing an article on the supporting arm, the pressure arm having an upwardly projecting folding finger adjacent the brush.

7. In a fabric straightening and guiding device the combination with fabric feeding mechanism of a fabric supporting arm directed toward said feeding mechanism and provided adjacent thereto with a bristle 120 brush arranged to engage the fabric supported on said arm and to straighten and guide the fabric to the feeding mechanism parallel with the ribs of the fabric.

8. A fabric straightening and guiding device comprising an arm having a rounded upper fabric supporting surface, a brush provided with bristles projecting above said supporting surface, and opposite finger notches adjacent the brush.

9. In a fabric straightening and guiding device the combination of a longitudinally slotted fabric supporting arm having a support at one end and provided adjacent the other end with a brush having bristles projecting a short distance above its upper surface, a lever pivoted in the slot of the arm and having an upturned end adjacent the brush, means tending to depress the upturned end of the lever and a connection for raising the upturned end of the lever.

10. In a fabric straightening and guiding device the combination of a fabric supporting arm provided adjacent one end with a bristle brush and adjacent the brush with opposite folding notches, and a folding finger movable into and out of operative position on the opposite side of the brush from said notches.

11. In a fabric straightening and guiding device the combination of an arm having an upper fabric supporting surface and a recess adjacent one end, and a brush held and vertically adjustable in said recess and having bristles projecting upwardly therefrom above the adjacent fabric supporting surface.

12. In a fabric straightening and guiding device the combination of an arm having an upper fabric supporting surface and gage points at one end, and a brush mounted on said arm adjacent the gage points and having bristles projecting upwardly above the fabric supporting surface.

In witness whereof I hereto affix my signature.

HUMPHREY EVANS.
